UNITED STATES PATENT OFFICE.

SAMUEL B. WILLIAMS, JR., OF BROOKLYN, AND EDWARD E. HINRICHSEN, OF NEW YORK, N. Y., ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed November 6, 1922. Serial No. 599,192.

To all whom it may concern:

Be it known that we, SAMUEL B. WILLIAMS, JR., and EDWARD E. HINRICHSEN, citizens of the United States of America, residing at Brooklyn, in the county of Kings and State of New York, and New York, in the county of New York and State of New York, respectively, have invented certain new and useful Improvements in Telephone-Exchange Systems, of which the following is a full, clear, concise, and exact description.

This invention relates to telephone exchange systems and more particularly to systems employing automatic switching apparatus for the establishment of conversational connections.

The object of the invention is a system of this character wherein certain equipment subject to frequent use is placed on a common basis thus reducing the amount of apparatus and increasing the general efficiency of the system.

A feature of the invention is the provision, in a system having a plurality of groups of circuits, each group accessible to a plurality of switches, of a common testing mechanism associable with any of said switches for testing any of the groups of circuits.

Another feature relates to the provision of a common set of testing relays and means for connecting said relays to any one of the selector switches for testing and selecting the circuits in any one of said groups.

A further feature relates to the provision, in a system having a plurality of coordinate selector switches each having links for making connection with the trunks of any of a number of groups, of a common testing mechanism connectable to any switch for testing the links thereof and the trunks of any of said groups thereon.

Further features and advantages of this invention will become apparent from the following description and from the appended claims.

Referring to the drawing, Figs. 1 to 14, inclusive, when arranged in the order illustrated in Fig. 15 discloses a sufficient portion of a telephone exchange system wherein the features of the invention are incorporated to enable a thorough understanding thereof.

Fig. 1 diagrammatically illustrates a line switch of the coordinate type in which the subscribers' lines terminate and also one of a number of trunks outgoing to a district selector switch.

Fig. 2 shows in diagram, a coordinate sender selector switch.

Figs. 3 and 4 show one of a number of common register senders. Fig. 3 illustrates the impulse receiving mechanism, including a set of counting relays, and Fig. 4 shows four numerical relay registers.

Fig. 5 discloses a district selector switch of the coordinate type in which terminate the trunks incoming from the line switches.

Fig. 6 illustrates a second district selector switch acting in the same capacity as the switch shown in Fig. 5 and having access to the same groups of outgoing trunks.

Fig. 7 represents a relay connector for connecting the register senders to a common district marker.

In the upper left hand corner of Fig. 8 and in Figs. 9 and 10, there is shown the district marker or selection controlling mechanism which is common to a plurality of district selector switches.

Fig. 11 illustrates a multi-contact relay connector for associating the district marker with the several district selector switches.

Fig. 12 shows diagrammatically a group selector switch in which terminate the trunks incoming from the district selectors.

Fig. 13 shows a coordinate connector switch for completing connections to the subscribers' lines.

In Fig. 14 and in the upper part of Fig. 8, there is shown a common line marker or selection controlling mechanism for determining the selective operations of the group selector and connector switches.

In the lower half of Fig. 8, there is illustrated, a relay connector device for connecting the register senders to the common line marker.

General description of the system and apparatus. 100

The telephone system herein disclosed employs an improved form of switching medium. The line switch 100, the district selector switches 500 and 600, the group selector switch 1200, connector switch 1300, and also the sender selector switch 200 are all of

the coordinate type comprising link circuits or trunks which serve to establish connections between incoming lines or circuits and outgoing lines or circuits.

- 5 The total number of subscribers' lines, of which four lines 101, 102, 112, and 113 are shown, enter the exchange and appear as calling lines in a number of coordinate line switches 100. Each trunk outgoing from the 10 line switches, such as the trunk 103, has an appearance in a sender selector switch 200 for the purpose of associating with these trunks any one of the register senders.

Also the trunks outgoing from the line 15 switches appear as incoming trunks in the coordinate district selector switches. There will be a number of these district selectors and each will accommodate a plurality of trunks. In the drawing, two district 20 selectors 500 and 600 are shown and the one trunk illustrated in full, namely trunk 103, appears in the district selector 500 and occupies the vertical row of contacts 501. The second trunk 104 shown outgoing from the 25 line switch 100 may appear in the vertical row 502 of the selector switch 500. Other trunks extending from the line switch 100 may also appear in the switch 500, utilizing other rows of contacts not illustrated. Still 30 other trunks extending from the line switch 100 may appear in other district selector switches as the switch 600. Again, the trunks outgoing from other line switches similar to the switch 100 may also be distributed 35 among the district selectors 500, 600, etc., in any desired manner. Two of the trunks 608 and 609, incoming from line switches and terminating in district selector switch 600, are illustrated.

40 The district selector switches have access to a plurality of groups of trunks outgoing to succeeding switches. In order that all subscribers' lines may have access to any of these outgoing trunks through the district 45 selector switches, it is necessary to multiple all trunks before all district switches. That is to say, each trunk in each group has a corresponding appearance in each of the several district selector switches. The district 50 selector switches may connect with groups of trunks of various characters leading in different directions. Some of these trunks may go to local switches while others may lead to distant offices. For the purpose of 55 the present discussion, however, only those groups of trunks leading to the local switches will be specifically considered.

Assuming that the local exchange has a 60 capacity of 10,000 subscribers' lines, these lines may be divided into five terminal groups of 2000 lines each. Each terminal group of 2000 lines is served by a number of group selector switches 1200, and a number of connector switches 1300. The district

selector switches have access to trunk groups 65 which lead directly to the switches of the terminal line groups. Hence, the several district switches are provided with five groups of trunks leading to the five different groups. These five groups of trunks appear in the 70 district selector 500 in the vertical rows such as 503, 504, 505, 506 and 507.

The district selector switches are equipped with horizontal link circuits or trunks 508, 509, 510, 511, etc., there being as many of 75 these links as the capacity of the switch requires. For example, it is assumed that each of the district selector switches has 70 of these link circuits divided into two sections, the upper and the lower sections of 80 the switch, each section containing 35 links. Regarding selector switch 500, the upper section is represented by links 508, 509, 510, 511 and 512 while the lower section is represented by links 513 and 517, inclusive. All 85 incoming trunks 103, 104, have access to all links in both sections and each link has access to one outgoing trunk in each of the vertical rows.

Depending upon the character of the 90 group of outgoing trunks, said group may occupy all or a portion of a vertical row in either the upper or lower sections or it may occupy the entire vertical row. Where a 95 small trunk group is sufficient, either the lower or upper half of a given row may be used.

Consider as an example, that each of the 100 five terminal line groups requires a group of 35 trunks outgoing from the district selector switch banks. The group of trunks leading to the first terminal group of 2000 lines which is assumed to be the one illustrated in the drawing, may occupy the upper half of the vertical row 507. The group of trunks leading to the second 2000 line group may appear in the lower half of the vertical row 507. The groups representing the third, fourth and fifth groups of 2000 105 lines may appear respectively in the upper and lower halves of the vertical row 506 and in the upper half of the vertical row 505. Other trunk groups extending from the district selector switch 500 occupying the vertical rows 504, 503 may be used for any 110 desired purpose such as interoffice calls.

As will be seen hereinafter, the common 115 district marker mechanism controls selection at any of the district switches. Where each group of outgoing trunks appear in all switches and may be reached through any one of the switches under the control of the marker, it is essential that every group of trunks are multiplied to all switches so as to have a corresponding appearance in all switches. With this provision, the marker will complete the selection in a given trunk group regardless of the district switch with 120 125

which it is associated. The group of trunks in the upper half of the vertical row 507, which includes trunks 545, 546, 547, 548 and 549, are therefore, multiplied to appear correspondingly in the upper half of the vertical row 607 of the district selector switch 600 and likewise in all other district selector switches. Similarly, the trunks of the group appearing in the lower half of the vertical row 507 and including trunks 550, 551, 552 are multiplied to appear in the lower half of the vertical row 607 of switch 600 and correspondingly in all other district switches. The same is true of all other trunk groups.

15 There being a plurality of register senders, a district marker sender connector 700 consisting of a number of multi-contact relays 701, 702 and 703 is provided for connecting the different senders to the marker.

20 The district marker shown in Figs. 8, 9 and 10, which is provided for the common use of a number of district switches, has for its function to receive part of the record initially established on the sender and to 25 use this record to determine selection of a group of trunks at the district switch. The district marker includes a set of register relays 800 which receive the thousands record from the sender and determine the 30 selection of the proper one of a number of group relays 900, 901, 902, etc. The district marker also comprises a set of testing relays including the two groups 1000 and 1001. The group of relays 1000 are used 35 for testing the respective trunks in any group appearing in the upper section of the district selectors. The group of testing relays 1001 serve to test corresponding trunks in any group or vertical row appearing in 40 the lower section of the district selector switches. The testing relays also serve to test the condition of the horizontal links or trunks in any district switch.

45 The testing relays of the marker are associated or connected with the different groups of outgoing trunks by means of multi-contact relay sets 905 and 906. For instance, the relay 909 serves to connect the group of relays 1000 to the testing wires of the group of trunks in the upper half of the vertical row 507 and multi-contact relay 912 serves to connect the group of testing relays 1001 with the test wires of the group appearing in the lower half of the 55 vertical row 507. The other multi-contact relays 908, 911, etc., serve similarly to connect the testing relays with the groups of trunks appearing in other vertical rows of the district switches.

60 For connecting the testing relays of the marker with the test wires of the horizontal links of the district switches there are provided two sets of multi-contact relays 1110 and 1111. The relay 1101 connects the

group of testing relays 1000 to the test wires 65 of the respective links 508, 509, 510, etc., in the upper section of the district selector 500. Relay 1103 connects the group of testing relays 1001 to the test wires of the respective links in the lower section of the 70 district switch 500. The other multi-contact relays 1102, 1104, etc., serve to connect the common testing relays to the horizontal links in other district selector switches.

As hereinbefore explained, the terminal 75 line group of 2000 lines is served by a number of group selector switches and a number of connector switches. For the particular terminal group illustrated, one group selector 1200 and one connector 1300 80 are shown in the drawing. While these switches are only partially illustrated, it will be understood that the group selector has a capacity for receiving any desired number of incoming trunks and is provided 85 with several vertical rows of outgoing trunks leading to the different connector switches 1300. It is also obvious that the connector switch 1300, which is only partially shown in the drawing, may have a 90 capacity for receiving the proper number of incoming trunks and a capacity for any desired number of outgoing subscribers' lines.

95 Each of the five terminal line groups of 2000 lines is further provided with a line marker or controlling mechanism for determining selection at the group selector and connector switches. The line marker is provided with a sender connector 801 comprising a number of multi-contact relays 808, 809, etc., for connecting the marker with any one of the register senders.

100 The line marker is equipped with two thousands register relays 1418, 1419 and 105 with the hundreds, tens and units registers 1400, 1401, and 1402, respectively, which receive the numerical record from the register sender. Moreover, the line marker has a translator mechanism 1404, and 1403 which 110 cooperates with the registers to determine the selective operations. There is also provided in the line marker, a set of common testing relays 802, for testing the trunks interconnecting the group selector and 115 connector switches.

120 As above mentioned, the selector switching devices employed in this system are of the coordinate type comprising intermediate or link circuits for connecting incoming lines to outgoing lines. The structure of the switch includes briefly a number of vertical operating bars which control contacts of the incoming and outgoing lines and a number of horizontal operating bars 125 which control contacts of the link circuits. The conjoint operation of two vertical bars and a horizontal bar causes the establish-

ment of the connection which is held solely by the horizontal bar after the vertical bars are released. For a complete description of the structure of a switch of this character, reference is made to the patent to S. B. Williams, No. 1,517,331, issued December 2, 1924, and to the British patent to Western Electric Company, Limited, No. 183,438, accepted September 6, 1923.

10 *Detailed description of establishment of a connection.*

Consider that the subscriber of line 101 desires to hold a conversation with the subscriber of the line 1316 appearing in the same central office. It may also be assumed that the directory number of the subscriber's line 1316 is 1234. The initiation of the call on the calling subscriber's line causes the 15 operation of the line switch 100 whereby the line is extended over an idle link 115 to idle trunk 103 extending to the district selector switch 500. Furthermore, the initiation of the call causes the operation of the sender 20 selector switch 200 and the calling subscriber's line is extended over the link circuit 202 and the circuit 204 to the idle register sender shown in the drawing. Had the sender illustrated been busy, the subscriber's line 25 would be extended over another circuit such as the circuit 205 leading to another sender, not shown. For an understanding of the manner in which calling lines are extended to idle trunks, and to idle senders, through 30 line switches and sender selectors of the coordinate type, reference is made to the patent to S. B. Williams above mentioned, No. 1,517,331. During the operation of the sender selector switch 200, a circuit may be closed 35 in any suitable manner for the relay 105. Relay 105 operates and closes a circuit from battery through the winding of slow-to-release relay 107, to ground at the inner left contact of relay 105. Relay 107 places 40 ground on the sleeve conductor 116 of the trunk 103. Relay 105 in operating, extends the tip and ring conductors of the trunk 103 through the sender selector 200 to the register sender mechanism. An impulse circuit 45 is thereupon completed as follows: battery through the resistance 318, winding of impulse relay 300, outer left contact of relay 303, conductor 319 through contacts of the sender selector switch 200, conductor 208, inner right contact of relay 105 thence over 50 the ring conductor of trunk 103 through contacts of the line switch 100 over the subscriber's line and returning over the tip conductor through the line switch 100, outer 55 right contact of relay 105, conductor 209, through contacts of the selector switch 200, conductor 320, inner left contact of relay 303, winding of the balancing coil 301 to ground. The impulse relay 300 operates 60 and closes a circuit for the slow-to-release 65

relay 302. Relay 302 completes a circuit from ground through its left contact, conductors 321, 322 through contacts of the switch 200, conductor 210, winding of relay 105 to battery. Relay 105 is held in this 70 circuit under the control of the relay 302 in the sender. Relay 302 also completes the circuit from ground through its contact over conductor 321, left contact of relay 305, left back contact of relay 304, winding of 75 slow-to-release relay 306 to battery. Relay 306 operates in this circuit.

The apparatus is now in condition for receiving the first series of impulses. The calling subscriber manipulates his impulse 80 transmitter to send the first series, in the present case consisting of a single impulse. at the time the relay 302 operates it closes a circuit from battery, resistance 339, through the left hand winding of relay 307 85 to ground at the right hand contact of said relay 302. Relay 307, however, does not operate since it is shunted by the following path: battery, resistance 339, through the right contact of relay 300 to ground at the 90 right contact of relay 302. In response to the first impulse, relay 300 releases and opens the shunt around the left hand winding of relay 307 and this latter relay operates. Relay 307 closes a circuit from battery through 95 the winding of relay 304, outer left contact of relay 307 to ground over conductor 321. Relay 304 operates and locks in a circuit through its left front contact, left contact of relay 305, to the grounded conductor 321. Relay 304 opens the original circuit of 100 relay 306. The latter relay now is energized in a circuit traceable through the outer right contact of relay 307 to ground over conductor 321.

Relay 307 closes a circuit through the left hand winding of relay 308 to ground at the inner left contact of relay 307. Relay 308 operates and closes a circuit from battery through its right hand winding and inner right contact to the grounded conductor 321. Relay 308 in operating, completes a circuit through its left hand winding and left contact, conductor 324, outer 110 right back contacts of counting relays 315, 314, 313 and 312 in series, winding of relay 312, outer left back contact of relay 313, conductors 325 and 326, outer right contact of relay 305, left front contact of relay 304, left contact of relay 305 to ground over conductor 321. So long as the relay 307 remains operated, however, relay 312 is shunted and does not receive sufficient current in the circuit traced to operate. At the 115 end of the impulse, the subscriber's line is closed, relay 300 operates and shunts relay 307 and this latter relay releases, opening the original circuit through the left hand winding of relay 308. Relay 312 now operates in series with the left hand winding of 120 125 130

relay 308. Relay 312 locks in a circuit, from battery over conductor 327, inner right contact of relay 312, winding of said relay, left back contact of relay 313 to ground over conductor 325.

It should be noted at this point that the armatures of the counting relay 312, and this is true of the remaining counting relays, are so arranged that the inner right contact 10 is closed slightly in advance of the opening of the outer right back contact. By this arrangement, the locking of the relay is sure to occur before the energizing circuit is opened.

15 Immediately that the relay 312 opens its back contact the circuit through the left hand winding of relay 308 is opened. Relay 308 is wound differentially and hence when the left hand winding is opened, the 20 effect of the right hand winding is to cause a quicker release. After an interval has elapsed following the impulse series, the slow-to-release relay 306 retracts its armature. A circuit now leads from ground over conductor 321, contact of relay 306, right contact of relay 304, inner right contact of relay 305, conductor 328, right back contact of relay 408, winding of relay 407 to battery. Relay 407 operates and connects 25 the control leads from the counting relays through to the thousands register 400. Relay 407 also completes a circuit from battery through its winding and inner upper contact, conductor 426, winding of relay 305, 30 right contact of relays 304 and 306 to the grounded conductor 321. Relay 305 does not operate at this time since its winding is shunted by the path previously traced through the winding of relay 407.

40 With relay 407 operated and the first counting relay 312 energized, a circuit is closed from ground over conductor 326, conductor 325, outer left front contact of relay 312, conductor 329, outer right back contact 45 of relay 317, conductor 330, lowermost contact of relay 407, windings of relays 404 and 406 to battery. A branch circuit also extends by way of conductor 427 through the winding of relay 423 to battery. These relays 50 all operate and lock in circuits traceable through the inner left contact of relay 404, conductor 428 to the holding conductor 321. Relay 406 completes a circuit from battery through the winding of relay 408 to the 55 grounded conductor 428. Relay 408 operates and locks through its inner left contact. Relay 408 opens the shunt around the winding of relay 305 and this later relay operates in series with relay 407. Relay 305 opens 60 the holding circuit of relay 304 and relay 304 releases to in turn open the circuit of relays 305 and 407. Relay 407 releases and disconnects the control leads from the registers.

65 The subscriber next manipulates his im-

pulse transmitter to send the second series of impulses representing the second digit. The control circuit operates in the manner described by the first impulse and when the second impulse is received, a circuit is closed 70 from battery through the left hand winding and left contact of relay 308, conductor 324 through the outer right back contacts of relays 315, 314 and 313 in series, outer right front contact of relay 312, winding of relay 75 313, outer left back contact of relay 314 to ground over conductor 325. Relay 313 operates and locks from battery over conductor 327 through its inner right contact and winding, outer left back contact of relay 80 314 to ground over conductor 325. Relay 313 at its outer left back contact opens the circuit of relay 312 and relay 312 releases.

After the proper interval has expired following the second series of impulses, relay 85 306 again becomes deenergized and a circuit is closed as follows: ground over conductor 321, right contacts of relays 306 and 304, inner right contact of relay 305, conductor 328, right front contact of relay 408, right 90 back contact of relay 412, winding of relay 411, to battery. Relay 411 operates and closes a circuit from battery through its winding and inner upper contact, conductors 430 and 426 winding of relay 305 and 95 thence to ground as traced. Relay 305, however, being shunted remains inert until relay 412 is operated. Relay 411 operates and extends the control conductors through to the second register 401.

With relay 411 operated and with the second counting relay 313 actuated, a circuit is completed from ground over the conductor 326 as hereinbefore traced, conductor 325, outer left front contact of relay 313, conductor 331, next to the lower contact of relay 411, winding of register relay 410 to battery. Relay 410 operates and locks through its winding and inner left contact to ground over conductors 431 and 421. 105 Relay closes a circuit from battery through the winding of relay 412, outer left contact of relay 410, to ground over conductor 431. Relay 412 becomes energized and locks 110 through its winding and left contact to the grounded conductor 321. Relay 412 opens the shunt around the winding of relay 305 and relay 305 operates in series with relay 411. Relay 305 opens the circuit of relay 304 and relay 304 releases to open the circuit of relay 305 and relay 411. Relay 411 disconnects the counting relays from the register 401. The impulse receiving circuit is 120 now in condition for the next series of impulses.

The subscriber next transmits the third series consisting of three impulses representing the third digit of the wanted number. The first two impulses cause the operation of counting relays 312 and 313 and the 130

release of relay 312. Upon the transmission of the third impulse, a circuit is completed through the left hand winding of relay 308 over conductor 324 through the outer right back contacts of relays 315 and 314, outer right front contact of relay 313, winding of relay 314, outer left back contact of relay 315 to ground over conductor 325. Relay 314 operates and locks through its inner right contact and winding and through the outer left contact of relay 315 to the grounded conductor 325. Relay 314 opens the circuit of relay 213. Relay 314 also opens the circuit of the left hand winding of relay 308 and this relay being differentiated releases immediately. After the elapse of a given interval following the third impulse, the slow relay 306 becomes deenergized and the circuit hereinbefore traced is closed by way of conductor 328 through the right front contacts of relays 408 and 412, right back contact of relay 416, winding of relay 415 to battery. Relay 415 operates and closes a circuit to battery through its winding and inner upper contact over conductors 430 and 426 through the winding of relay 305 as traced to ground. Relay 305 does not operate at this time.

With relay 415 and relay 314 operated, a circuit may be traced from ground over conductor 326 through the outer left front contact of relay 314, conductor 330, lower-most contact of relay 415, winding of relay 413 to battery. Another circuit is closed from ground over conductor 326 through the inner left contact of relay 314, conductor 331, next to the lower contact of relay 415, winding of relay 414 to battery. Relays 413 and 414 operate and lock in circuits from battery through the windings and inner left contacts to ground over conductors 432 and 321. Relay 413 closes a circuit from battery through the winding of relay 416, outer left contact of relay 413, to the grounded conductor 432. Relay 416 locks in a circuit through its winding and left contact to the grounded conductor 321. Relay 416 opens the shunt around the winding of relay 305 and this latter relay operates in series with relay 415. Relay 305 in the manner already explained opens the circuit of relay 304 whereupon relays 305 and 415 are deenergized, and the sender is placed in condition for receiving the last series of impulses.

The calling subscriber sends the last series of four impulses in response to the first three of which relays 312, 313 and 314 are operated in succession and relays 312 and 313 are released in succession. The fourth impulse causes the operation of relay 308 and the previously traced circuit is closed from battery through the left hand winding of this relay over conductor 324 hence through the outer right back contact of re-

lay 315, outer right front contact of relay 414, winding of relay 315, outer left back contact of relay 316 to ground over conductor 325. Relay 315 operates and locks through its inner right contact and winding and the outer left back contact of relay 316 to the grounded conductor 325. Relay 315 opens the circuit of relay 314 and also the circuit through the left hand winding of relay 308. Relay 308 is then released. After an interval has expired, slow relay 306 releases and the circuit already traced is completed from ground over conductor 328 through the right front contacts of relays 408, 412, and 416 right contact of relay 420, winding of relay 419 to battery. Relay 419 operates, extending the control leads from the counting relays through to the units register 403, and also closes a circuit through its winding and inner upper contact thence over conductor 430 as hereinbefore traced through the winding of relay 305 to ground. Relay 305, however, being shunted does not operate at this time.

With relay 419 and relay 315 operated, a circuit is completed from ground over conductors 326 and 325 through the outer left back contact of relay 312, inner left contact of relay 315, conductor 332, next to the inner lower contact of relay 419, winding of register relay 433 to battery. Relay 433 locks through its inner left contact to ground over conductors 434 and 321. Relay 433 closes a circuit from battery through the winding of relay 420, outer left contact of relay 433 to the grounded conductor 434. Relay 420 removes the shunt from the winding of relay 305 and this latter relay operates in series with relay 419. Relay 305 in the manner explained, causes the release of relay 304 which in turn causes the release of relays 305 and 419.

As soon as the first or thousands digit is recorded on the register 400, the sender is connected to the district marker in order that the record of the thousands digit may be transferred to the register 800 for determining the group selective operation at the district switch. This operation takes place immediately without waiting for the subscriber to send the remaining series of impulses. When relay 408 operates, it completes a circuit from battery through the winding of relay 309, conductor 333, outer left contact of relay 408, conductors 428 and 321 to ground at the left contact of relay 302. Relay 309 attracts its armature and closes a circuit over the grounded conductor 321, outer left back contact of relay 311, contact of relay 309, conductor 334, winding of relay 709 to battery. Relay 709 operates and completes a circuit from ground through its right contact, conductor 716, right contact of relay 711, winding of relay 712 to battery. Relay 712 operates and a

- circuit is closed from battery through the right hand winding of relay 706, left contact of relays 709, 708, 707 and 712, right back contact of relay 710, right contact of relay 715 to ground. Relay 706 operates and closes a circuit from battery through its left hand winding and left contact, left back contacts of relays 705 and 704, left contact of relays 711, winding of relay 710 to ground at the contact of relay 715. Relay 706 locks and relay 710 is operated in this circuit. It will be noted that the relay 711 operates over a circuit closed at the inner right contact of relay 706. Relay 711 opens the original circuit of relay 712 but relay 712 is held in a locking circuit from battery through its winding and right contact and right back contact of relay 710 to ground at the contact of relay 715. Immediately that relay 710 operates, relay 712 releases. Relay 706 closes a circuit from battery through the winding of multi-contact relay 703, outer right contact of relay 706, inner left contact of relay 710 to ground at the contact of relay 715. Relay 703 operates and extends the control conductors from the register sender shown through to the district marker. Relay 703 also closes a circuit from ground through its contact, outer left contact of relay 710, inner left back contact of relay 714, winding of relay 713, to battery.

When the register sender is connected to the district marker in the manner just described, a circuit is completed for operating the particular vertical magnet controlling the row of vertical contacts which represent on the district selector switch, the trunk 103 over which the calling subscriber's line has been extended to said district selector. Since the trunk 103 appears in the vertical row of contacts 501 in the district selector switch 500, this circuit serves to energize the corresponding vertical operating magnet 518. The circuit may be traced as follows: ground through the contact of relay 715 in the district marker, right front contact of relay 710, outer left contact of relay 713, conductor 718, contact of relay 703, conductor 719, left contact of relay 311, conductor 335, contacts of switch 200, conductor 212, back contact of relay 110, conductor 118, winding of magnet 518 to battery. Magnet 518 operates and prepares the contacts in the row 501 for connecting the trunk 103 to any one of the link circuits.

With the thousands register relay 404 operated, and relays 405, 435 and 436 deenergized a circuit may be traced from ground through the contact of relay 715, conductor 720, inner contact of relay 713, conductor 721 contact of relay 703, conductor 722, outer right back contact of relay 422, right back contacts of relays 436, 435 and 405 in series, conductor 437, inner right back contact of

relay 422, conductor 438, contact of relay 703, conductor 723, winding of relay 807 to battery. Relay 807 operates and a circuit is closed from ground over conductor 720, contact of relay 807, conductor 840, winding of group relay 904 to battery.

At the time relay 713 operated a circuit is closed from ground through the contact of relay 715 to conductor 718 as traced thence over conductor 724, outer left back contact of relay 918, winding of slow-to-release relay 919, to battery. Relay 919 operates and closes a circuit for slow-to-release relay 920.

At the time the vertical operating magnet 518 is energized, a circuit is closed from battery through the winding of relay 109, conductor 119, outer contact of magnet 518, conductor 120, outer left contact of relay 105 to ground over conductor 116. Relay 109 operates and locks in a circuit from battery through its winding and inner left contact, conductor 120, through the outer left contact of relay 105 to the grounded sleeve conductor 116.

At the time the vertical operating magnet 518 was operated, a circuit is completed from ground through the inner contact of said magnet, conductor 525, thence in parallel through the windings of multi-contact relays 1101 and 1103 to battery. Another circuit is traceable from ground through the inner contact of magnet 518, conductors 525 and 526, winding of multi-contact relay 916 to battery. Relays 1101 and 1103 are individual to the district selector switch 500 and serve as hereinbefore explained to associate the common testing relays 1000 and 1001 with the horizontal link circuits of said selector switch. The relay 916 is also individual to the district selector 500 and serves to associate the group relays 900, 901 and 902, etc., with said district selector in order to select and operate a particular vertical magnet 540, 541, 542, 543, 544, etc., which controls the vertical row of contacts representing the selected group of outgoing trunks.

Returning to the point where the group relay 904 is operated, a circuit is closed from ground through the lowermost contact of relay 904, winding of relay 918 to battery. Relay 918 completes a circuit from ground through its inner left contact, right front contact of relay 920, conductor 922, inner lower contact of relay 904, conductor 923, contact of relay 916, conductor 924, winding of vertical operating magnet 544 to battery. The magnet 544 rotates its associated bar and prepares the contacts of the trunks in the row 507 for connection to the horizontal trunks. Relay 918 opens the circuit of relay 919. Relay 919 being slow-to-release does not retract its armatures immediately. Relay 918 also completes a circuit from ground over conductor 724, outer left front contact of said relay, left contact of relay 130

920, conductor 925, contact of relay 916, conductor 926, uppermost contact of relay 904, winding of relay 909 to battery. Relay 909 operates and connects the group of testing 5 relays 1000 with the test conductors of the selected group of trunks appearing in the upper half of the vertical row 507 at the district selector.

Immediately that the relay 909 operates an 10 instantaneous testing operation takes place and the testing relays 1000 are operated or refuse to operate according to the condition of the respective trunks of the outgoing group and also according to the condition of 15 the horizontal link circuits of the district selector switch. For the sake of illustration, it will be considered that links 512 and 511 are idle, links 510 and 509 are busy and that link 508 is idle. Furthermore, assume that 20 the outgoing trunks 549 and 548 accessible respective to the links 512 and 511 are busy and that the trunks 547, 546 and 545 accessible respective to the links 510, 509 and 508 are idle, busy and idle respectively. Observing 25 the conditions mentioned, it will be seen that the first trunk in the group which is idle and which is reached over a horizontal link that is also idle, is the trunk 545. Since the trunk 549 is busy, a test circuit is closed 30 from battery through the right hand winding of testing relay 1014, right contact of relay 1016, conductor 1032, contact of relay 909, conductor 927, grounded busy testing conductor 527 of the trunk 549. Relay 1014 35 operates in this circuit and locks from battery through its right winding and right contact, conductors 1033 and 1034 to ground at the outer right contact of relay 918. Relay 1014 closes a circuit from battery 40 through the winding of relay 1015, left contact of relay 1014 hence to ground over conductors 1033 and 1034. Relay 1015 closes a circuit from ground through the winding of relay 1016 to ground at the outer left contact of relay 1015. Since the next trunk 548 45 is busy, a circuit is closed from battery through the right hand winding of relay 1011, back contact of relay 1013, conductor 1035, contact of relay 909, conductor 928 to the grounded test conductor 528. Relay 1011 50 operates and locks to the grounded conductor 1033. In a similar manner to that described, relay 1011 causes the operation of the associated relays 1012 and 1013. Since the link 510 55 is considered to be busy, a circuit is traceable from battery through the left hand winding of corresponding testing relay 1008, outer left back contact of relay 1010, conductor 1036, contact of relay 1101 conductor 60 1112 to the grounded test conductor 530 of the busy link 510. Relay 1008 operates in this circuit and in the manner explained causes the operation of the associated relays 1009 and 1010. Since the trunk 546 is busy, 65 a circuit is closed from battery through the

right hand winding of relay 1005, right contact of relay 1007, conductor 1037, contact of relay 909, conductor 929 through the busy test conductor 531. Moreover, a circuit is closed from battery through the left hand winding of relay 1005, conductor 1038, outer left back contact of relay 1007, conductor 1039, contact of relay 1101, conductor 1113, to the busy test conductor 532 of link 509. Relay 1005 becomes energized and causes the 70 operation of relays 1006 and 1007. In a similar manner, a path may be traced from battery through the right hand winding of testing relay 1002 to the test conductor 533 of trunk 545 and a path may be traced through the left hand winding to the test conductor 534 of link 508. Under this assumption, however, both the trunk 545 and the link 508 are idle, therefore, the relay 1002 75 remains deenergized.

After an interval has expired following the operation of relay 918, the relay 919 becomes deenergized and opens the circuit of relay 920. Relay 920, however, is slow-to-release and does not retract its armatures at 80

It will be noted at this point that the relay 917 is energized at this time in a circuit traceable battery through the winding of said relay, conductor 930, through the contact of relay 916, conductor 931 to ground at the contact of the operating magnet 544.

With relay 917 operated, and relay 919 released, a circuit is closed from ground over conductor 724 through the right contact of relay 917, right contact of relay 919, inner right contact of relay 918, contact of relay 909 to the start conductor 933, inner left front contacts of relays 1015, 1012, 1009 and 1006 in series, inner left back contact of relay 1003, winding of relay 1004 to battery. Relay 1004 operates in this circuit and a circuit is established as follows: ground through the left contact of relay 917, conductor 934, right front contacts of relays 1015, 1012, 1009 and 1006, right back contact of relay 1003 thence through the left front contacts of relay 1004, conductors 1040 and 1041, contacts of relay 1101, conductors 1114 and 1115 windings of horizontal operating magnet 520 to battery. The magnet 520 rotates the associated operating bar and incoming trunk 103 is connected through the link 508 to the respective conductors of the outgoing trunk 545. Immediately that the trunk 103 is connected to the link, a circuit is closed from battery to the right hand winding of magnet 520, contacts of the switch 500, conductor 116 of the trunk 103 thence to ground at the contact of relay 107. The magnet 520 is held operated in this circuit independent of the district marker.

After another interval has expired, the relay 920 becomes deenergized and opens the circuit of relay 909. Relay 909 releases and 125

disconnects the testing relays 1000 from the outgoing trunk group. Relay 920 also opens the circuit of vertical magnet 544. The magnet 544 restores the associated bar to its normal position. Relay 909 opens the start circuit whereby the energizing circuit for the horizontal magnet 520 is opened and this magnet is now held solely over the sleeve conductor 116. Relay 920 moreover closes a circuit from ground through the inner left contact of relay 918, right back contact of relay 920, conductor 935, winding of relay 714, to battery. Relay 714 operates and locks in circuit through its winding and inner left front contact, outer left contact of relay 710 to ground at the contact of relay 703. Relay 714 closes a circuit for relay 715 but this latter relay being slow-to-operate and slow-to-release consumes an appreciable interval of time before its contact is opened. Relay 714 opens the circuit of relay 713 and relay 713 releases.

While relay 714 is operated, and while relay 715 is operating, a circuit is closed momentarily from ground through the contact of relay 715, right contact of relay 714, conductor 725, contact of relay 703, conductor 726, winding of relay 311, to battery. Relay 311 operates and locks in a circuit through its outer right contact to the grounded conductor 321. After an interval, relay 715 attracts its armature and ground is removed from conductor 720, whereby relays 714, 710, 706 and 703 become deenergized. The release of multi-contact relay 703 disconnects the register sender from the district marker mechanism. The disconnection of the marker causes the release of relays 807, 904, 917 and 918. When the district marker is disconnected, the previously traced circuit of vertical magnet 518 is also opened. Magnet 518 releases the associated bar to its normal position. Magnet 518 also opens the energizing circuits of multi-contact relay 916, 1101 and 1103. The district marker is now fully restored and may be taken again for association with another sender and with the same or another district selector switch. Magnet 518 also closes a circuit from battery through the winding of relay 110, outer left front contact of relay 109, outer back contact of magnet 518, conductor 120, outer left contact of relay 105 to ground on conductor 116. Relay 110 operates and locks to the grounded conductor 120.

Provided at this time, the subscriber has completed the transmission of the last three series of impulses, a circuit is closed for the relays 425, 421 and 422. Provided the marker is disconnected before the units series of impulses is completed, the circuit for said relays will be held open until such time as the units impulses have been received. The circuit referred to, may be followed from battery through the windings of relays 421,

422 and 425 in parallel thence over conductor 439, inner right contact of relay 311, inner left contact of relay 310, conductor 336 to ground at the outer left contact of relay 420, which operates when the units series of impulses has been transmitted.

The operation of relays 421 and 422 serves to bring about the connection of the register sender to the particular line marker shown in Figs. 8 and 9 which serves the first group of 2000 lines containing the called subscriber's line. Relay 422 in operating, completes a circuit from ground through the outer left contact of relay 420, conductor 336, thence over the path already traced to the conductor 439, outer right front contact of relay 422, left back contacts of relays 436, 435 and 405, conductor 437, inner right front contact of relay 422, conductor 440, winding of relay 812 to battery. Relay 812 operates and closes a circuit from ground through its right contact, right contact of relay 815, winding of relay 816, to battery. Relay 816 operates and locks through its right contact, outer right back contact of relay 814 to ground at the contact of relay 817. Relay 816 closes a circuit from battery through the right hand winding of relay 810, left contact of relay 812, left contact of relay 813, left contact of relay 816 thence to ground as traced at the right hand contact of relay 817. Relay 810 operates and at its inner right contact closes an energizing circuit for relay 815. Relay 815 operates and a circuit is closed from ground through the left hand winding and left contact of relay 810, left back contact of relay 811, left contact of relay 815, winding of relay 814, to ground at the contact of relay 817. Relay 810 locks and relay 814 becomes energized in this circuit. The operation of relay 816 opens the energizing circuit and the operation of relay 814 opens the locking circuit of relay 816. A circuit is now completed from battery through the winding of multi-contact relay 808, outer right contact of relay 810, inner left contact of relay 814 to ground at the contact of relay 817. Multi-contact relay 808 operates and connects the register sender to the line marker. Relay 808 also closes a circuit from ground through its contact, outer left contact of relay 814, outer left back contact of relay 819, winding of relay 818 to battery.

As soon as the line marker is connected to the sender, a circuit is closed for the vertical magnet 1206 of the group selector switch 1200 which controls the row of contacts representing the incoming trunk 545, selected by the district selector switch 500. This circuit may be traced from ground through the contact of relay 817, conductor 841, inner right contact of relay 814, contact of relay 818, conductor 843, contact of relay 808, conductor 844, contact of relay 425, conductor

441, outer right contact of relay 310, conductor 337, contacts of sender selector switch 200, conductor 213, inner right front contact of relay 109, tip conductor of the trunk 103, 5 through the contacts of the district selector switch 500 to the tip conductor of trunk 545, contact of relay 1218, winding of magnet 1206 to battery. Magnet 1206 operates and prepares the contacts of the group selector for connecting the incoming trunk to any one of the horizontal trunks 1203, 1204, 1205, etc. Magnet 1206 completes a circuit from ground at its contact, conductor 1220, winding of multi-contact relay 1212 to battery. 10 Relay 1212 operates and connects the set of testing relays 802 in the line marker, to the testing conductors of the link circuits of the group selector.

The thousands, hundreds, tens and units 20 registrations are now transferred from the sender to the line marker in the manner about to be described. Since the thousands digit of the wanted line is 1 and only the first relay 404 of register 400 is operated, a circuit is completed from ground over conductor 841, through the inner right contact of relay 814, and the contact of relay 818 to conductor 843 thence as previously traced over conductor 844, contact of relay 423, conductor 442, contact of relay 808, conductor 845, winding of relay 1419 to battery.

Since only the hundreds register relay 410 is actuated, a circuit is completed from ground over conductor 841 of the line 30 marker as previously traced through the conductor 844, right contact of relay 410, conductor 443, contact of relay 808, conductor 846, winding of relay 1415 to battery.

With the relay 413 of the tens register operated, a circuit is completed over the grounded conductor 844 through the right contact of relay 413, conductor 445, contact of relay 808, conductor 847, winding of relay 1406 to battery. Another circuit is closed 40 from ground over conductor 844 through the right contact of relay 414, conductor 446, contact of relay 808, conductor 848, winding of relay 1407 to battery.

Since the units register relay 433 is energized, the circuit is closed from ground over conductor 844 through the right contact of said relay, conductor 447, contact of relay 808, conductor 849, winding of relay 1412 to battery.

55 Relay 1419 may represent the odd or No. 1 thousand of the 2000 line group and when energized as explained completes a circuit as follows: ground over conductor 841, inner right contact of relay 814, contact of relay 818, conductor 843, front contact of relay 1419, right back contact of relay 1418, winding of multi-contact relay 1427 to battery. Relay 1427 operates and connects the leads from the tens register 1402 to the lower half of the translator device 1404. The

hundreds register 1400 brings about the closure of the following circuit: ground over the conductor 843 as traced conductors 850 and 851, inner right contacts of relays 1417 and 1416, inner right front contact of relay 1415, inner left back contact of relay 1414, conductor 1429, multi-contact relay 1430 to battery.

With relay 1427 operated and one of the hundreds relays energized, such as relay 1430, a circuit is closed from battery through the winding of relay 1439, contacts of relays 1427 and 1430, to the grounded conductor 850.

The tens register 1402, now determines the closure of a circuit from ground over the conductor 850, contact of relay 1439, inner right back contacts of relays 1409 and 1408, inner right front contact of relay 1407, inner left front contact of relay 1406, conductor 1431, contact of relay 1427, conductor 1432, contact of relay 1430, conductor 1433, winding of vertical magnet 1315, serving the vertical row of contacts in the connector switch 1300 in which appears the calling 90 subscriber's line 1316. Magnet 1315 operates and prepares the contacts in the associated row.

Magnet 1315 completes a circuit from ground through its contact, conductor 1317, winding of multi-contact relay 1216, to battery. Relay 1216 operates and associates the testing relays 802 of the line marker with the group of trunks interconnecting the group selector switch 1200 and the connector 1300. Relay 1216 completes a circuit from ground through its contact, conductor 1121, winding of vertical magnet 1208 to battery. Magnet 1208 prepares the contacts of the row containing the trunk 105 1222, leading to the connector switch 1300 for operation. Magnet 1208 also completes a circuit from ground at its contact, contact of relay 1212 conductor 1223, winding of relay 821 to battery. Relay 821 closes a circuit for the relay 820.

A branch of the circuit just traced for relay 1216 also extends from conductor 1317 by way of conductor 1318 through the winding of multi-contact relay 1420 to battery. With relay 1420 operated, a circuit is completed by way of the grounded conductor 850 thence over conductor 1434, inner right back contact of relay 1413, inner right front contact of relay 1412, conductor 1435, contact of relay 1420, conductor 1436, winding of multi-contact relay 1311 to battery. Relay 1311 operates and associates the testing relays shown in upper left hand corner of Fig. 14 with the group of horizontal connecting trunks 1301, 1302, etc., of the connector 1300 which have access to the calling subscriber's line.

The testing of the trunks of the group extending from the group selector group 1200 130

to the connector switch 1300 will next be described. If the first trunk 1224 shown in the group is busy, a circuit is closed from battery through the right hand winding of relay 834, innermost right contact of relay 836, conductor 859, contact of relay 1216 to the grounded test conductor 1226 of trunk 1224. If the link 1227 having access to the trunk 1224, is busy, a circuit is completed from battery through the left hand winding of relay 834, outer left back contact of relay 836, conductor 854, contact of relay 1212, to the grounded test conductor 1228 of the link 1227. Similarly, circuits may be traced through the windings of relay 831 in case the trunk 1225 and the link 1205 are busy. The test relays 834 and 831, etc., operate either winding or both windings and hence if either the trunk 1224 or the corresponding link 1227 is busy, relay 834 is operated. Relay 834 locks through its right hand winding, conductor 855, right contact of relay 821 to the grounded conductor 843. Relay 844 closes a circuit from battery through the winding of relay 835, left contact of relay 834 to ground over conductor 855. Relay 835 closes a circuit for relay 836. If either the trunk 1225 or the link 1205 is busy or both are busy, relay 831 is operated, locks to the grounded conductor 855 and causes in a similar manner, the operation of relays 832 and 833. Assuming, however, that trunk 1222 and the corresponding link 1204 are both idle at this time, the respective testing relay 828 remains inert.

When relay 821 operates, it closes a circuit from ground through its inner left contact, conductor 856, right contact of relay 837, winding of slow-to-release relay 838 to battery. Relay 838 operates and closes a circuit from battery through the winding of slow-to-release relay 823, inner contact of relay 838 to ground over conductor 843. Relay 823 closes a circuit from battery through the winding of slow-to-release relay 824, right front contact of relay 823 to ground over conductor 843. Relay 824 completes a circuit from battery through the winding of relay 825 front contact of relay 824, outer right front contact of relay 814 to the grounded conductor 841. A circuit may now be traced to ground over conductor 843, through the outer left contact of relay 821, start conductor 857, inner left front contacts of relays 835 and 832, inner left back contact of relay 829, winding of relay 830 to battery. Relay 830 operates and a circuit is established from ground over conductor 843 through the right contact of relay 821, conductor 855, outermost right contact of relay 830, outer right contact of relay 829, conductor 858, contact of relay 1216, conductor 1230, winding of vertical operating magnet 1313 to battery. Magnet 1313 operates and prepares the con-

tacts of the selected idle trunk 1222 for connection with the horizontal links of the connector switch 1300. Magnet 1313 completes a circuit from ground through its contact, conductor 1319, winding of relay 837 to battery. Relay 837 operates and opens the circuit of relay 838. Relay 838, however, being slow, retains its armatures for an appreciable interval of time. Relay 837 completes a circuit over the grounded conductor 855, and left contact of said relay, conductor 860, contact of relay 1311, winding of the horizontal magnet 1309 to battery. Magnet 1309 operates the auxiliary horizontal test trunk 1303 which is common to all connecting trunks 1301, 1302, etc., in the group having access to the called subscriber's line. Since the vertical magnets 1313 and 1315 are both operated, the operation of magnet 1309 at this time connects the horizontal test connector 1303 with the test conductor of the trunk 1232 and also to the test conductor of the subscriber's line 1316.

The testing and selecting of an idle link at connector switch 1300 will now be described. Assume that the link 1301 is already busy in connection with another call. A circuit may then be traced from battery through the right hand winding of testing relay 1422, left contact of relay 1421, contact of relay 1311, conductor 1320, to the ground over the test conductor of the busy link 1301. Relay 1422 operates and locks through its left hand winding to the grounded conductor 843. If the next link 1302 is idle, the relay 1424 remains deenergized. The condition of the remaining test relays 1426, etc., will depend upon the condition of the corresponding links in the group.

After the proper interval has expired, slow relay 838 releases and the testing circuit for testing the condition of the called line 1316 is completed as follows: battery through winding of relay 822, left contact of relay 823, left back contact of relay 838, middle right contact of relay 830, outermost right back contact of relay 829, conductor 861, contact of relay 1216, over the test conductor 1232, horizontal testing link 1303 to the test conductor 1321 of the called line 1316. Assuming that called line is idle, no ground potential occurs on conductor 1321, and relay 822 fails to operate. After an interval following the release of relay 838, slow relay 823 becomes deenergized. With relay 823 deenergized, a circuit is completed from ground over conductor 843, right back contact of relay 823, right contact of relay 822, thence through the outer left contact of relay 825, conductor 862, innermost right front contacts of relays 835 and 832, innermost right back contact of relay 829 thence through the left front contacts of relay 830, conductors 863 and 864, contacts of relay

1212, windings of horizontal magnet 1209 to battery. The magnet 1209 operates the associated bar and the trunk 545 is connected through the link 1204 to the trunk 5

1222. When the connection is established, a circuit is closed from battery through the winding of relay 1217, sleeve conductor 1233, contacts of the switch 1200 thence through contacts of the relay 1212 to the 10 grounded conductor 863. Relay 1217 operates and locks through its winding and left contact to the grounded sleeve conductor 533. Moreover, relay 1217 extends ground over conductor 433 through its left contact, 15 conductor 1233, contacts of switch 1200 through the right hand winding of magnet 1209 to battery. Thus the horizontal magnet 1209 is held under the control of the sleeve conductor and independent of the line 20 marker. Relay 1217 closes a circuit for relay 1218 which at its contact, opens the circuit of the vertical magnet 1206. Magnet 1206 restores the associated bar and also opens the circuit of multi-contact relay 25 1212. Relay 1212 disconnects the test relay 802 from the group selector switch 1200.

Relay 823 in releasing, completes another circuit, which may be traced from ground over conductor 843, right back contact of 30 relay 823, right contact of relay 822, inner left contact of relay 825, conductor 866, right front contact of relay 1422, right back contact of relay 1424, winding of relay 1423 to battery. Relay 1423 operates and the 35 grounded conductor 866 is extended through the right contacts of said relay by way of conductor 1437, contact of relay 1311, conductor 1323, left hand winding of magnet 1308 to battery. Magnet 1308 rotates the associated bar and the trunk 1222 is connected through link 1303 to the calling subscriber's line 1316. Immediately that the 40 connection is effected, a circuit is closed from battery through the right hand winding of magnet 1308, contacts of switch 1300, sleeve conductor 1232 of the trunk 1222, through contacts of the group selector 1200 to the grounded sleeve conductor 1232. Magnet 1308 is maintained energized in this circuit. 45

After an interval following the release of relay 823, relay 824 becomes deenergized. Relay 824 closes a circuit from battery through the winding of release relay 819, outer right contact of relay 825, back contact of relay 824, outer right front contact of relay 814, to ground over conductor 841. Relay 819 operates and locks in a circuit through its winding and outer right front contact, outer left contact of relay 814, to ground at the contact of relay 808. Relay 819 closes a circuit for relay 817. Relay 817 being slow-to-release and slow-to-energize does not attract its armatures immediately. Relay 819 at its outer left back contact opens the circuit of relay 818 which

becomes deenergized removing ground potential from conductor 843. The removal of ground from conductor 843 permits the release of the energized relays in the line marker. The restoration of the line marker 70 relays causes the deenergization of the vertical operating magnets 1208, 1313 and 1315 and the connection is held through the selector switches by the continued energization of magnets 1209 and 1308. 75

During the interval that relay 819 is operated, and before relay 817 attracts its armature, a circuit is completed momentarily from ground through to contact of relay 817, right contact of relay 819, conductor 867, contact of relay 808, conductor 868, winding of relay 310 to battery. Relay 310 operates and locks to the grounded conductor 321. After an interval, relay 817 operates and opens the holding circuit of relays 814 and 810. These relays become deenergized causing a release of the multi-contact relay 808 and the disassociation of the line marker from the sender. 80

The operation of relay 310 initiates the 90 release of the register sender. Relay 310 completes a circuit from battery through the winding of relay 303, outer left contact of relay 310, conductor 336, to ground at the outer left contact of relay 420. Relay 303 becomes energized and locks through its right contact to the grounded conductors 322 and 321. Relay 303 at its left contacts, disconnects the impulse relay 300 and the balancing coil 301 from the calling subscriber's line 101. Relay 300 releases and opens the circuit of slow relay 302. After an interval, relay 302 retracts its armatures and removes the ground from the holding conductor 321 whereupon all energized relays in the register sender and registers are 95 permitted to release. 100

The removal of ground from holding conductor 322 may cause the release of the 105 sender selector switch 200 in any suitable manner. The removal of ground from conductor 322 also causes the release of relay 105. Relay 105 disconnects the subscriber's line from conductors 208 and 209 and extends said line through to the left hand windings of repeating coil 108 in the trunk. Relay 106 operates in series with the calling line and completes a holding circuit for slow relay 107 whereby ground potential is 110 maintained on the sleeve conductor 116 to hold the connection. The release of relay 105 opens the holding circuit of relays 109 and 110. Relay 109 on deenergizing, completes the tip and ring conductors of the trunk 115 through to the district switch. 120

In any well known and approved manner, ringing current may be applied to the calling subscriber's line. 125

After conversation the subscribers replace 130 their receivers on the switchhooks and relay

106 releases. After an interval, relay 107 becomes deenergized and withdraws ground potential from conductor 116. Thereupon the holding circuits of the horizontal magnets of the district selector switch 500, group selector switch 1200 and connector switch 1300. These magnets 520, 1209 and 1308 release the associated bars and disconnect the trunks and links.

10 In the example taken, it was assumed that the group of trunks selected at the district switch 500 occupies the upper half of one of the vertical rows such as 507. In this case, the group of testing relays 1000 was 15 associated through the contacts of the corresponding relay in the set 905 with the test conductors of said group of trunks. Moreover, the testing relays 1000 were associated through the contacts of a corresponding relay in the set 1110 with the horizontal trunks or links in the upper section of the switch 500. Should it be desired to select a group of trunks in the lower section of the district switch 500, such as the group 20 occupying the lower half of the vertical row 507, the other group of testing relays 1001 are connected through contacts of the multi-contact relay 912 to the test conductors of said group of trunks. Furthermore, the 25 testing relays 1001 are connected through the contacts of the proper relay in the set 1111 with the horizontal links in the lower half of the district switch 500.

Should the connection involve another of 30 the district selectors such as the switch 600, the common testing relays are associated in a similar manner through the multi-contact relay 905 and 906 with the test conductors of the selected group of trunks and also 35 through the contacts of the relays 1110 and 1111 with the horizontal link circuits of the district selector switch 600. The same is true for any district selector switch that may 40 be used in the extension of a connection.

45 Should other thousands digits be involved, relays 1418 and 1419 operate in various combinations to control relays 1427 and 1428.

It was explained that the testing relays 50 1014, 1011, 1008, 1005, etc., have two windings. One winding is used for testing the corresponding outgoing trunk in any of the several groups while the other winding is used for testing the horizontal link of any 55 district switch which has access to each of the said corresponding outgoing trunks. Either winding is sufficient to operate the relay or when both windings are energized the relay also operates to indicate that the trunk is not available.

60 Summarizing briefly, it may be stated that the testing equipment comprising the two groups of relays 1000 and 1001 is located in the marker and is common to a plurality of district selector switches, is associative with any switch and with one of a number

of groups of trunks accessible to all switches and is associative with the link circuits on any particular switch.

While the invention has been illustrated in connection with a system employing selective switchings of the coordinate type, it is understood that no limitations concerning the character of the switches used, or the method of controlling other operations, is intended. The principle of the invention is 75 applicable to other types of systems.

In case it is desirable to assign an entire vertical row of terminals in the district selector switches, a single group of outgoing trunks this may be done by arranging for 80 the operation of a multi-contact relay in both of the sets 905 and 906. For example, if the row 503 of the district switch 500 represents a single group of trunks, the particular group relay 900 which characterizes 85 this group of trunks causes the operation of both the multi-contact relays 907 and 910. Thus both sets of testing relays 1000 and 1001 are connected to the trunks of the outgoing group and to the horizontal links 90 for the selection of an idle trunk and a corresponding idle link.

For a more detailed understanding of the operation of a system of this character, a general reference is made to the patent to 95 S. B. Williams, No. 1,517,331, granted December 2, 1924.

What is claimed is:

1. In a telephone system, a group of circuits, a number of switches, each having access to said circuits, a common testing mechanism, means for connecting said mechanism to and disconnecting the same from the circuits of said group for testing the same, means for associating the mechanism with 100 any of said switches, and means for operating the associated switch to select one of said circuits.

2. In a telephone system, a group of outgoing trunks, a number of selector switches, 110 each having access to all of said trunks, a common testing mechanism, a variably operable device for connecting said mechanism to the trunks of said group for testing the same, means for associating the mechanism 115 with any of said switches, and means for operating the associated switch to select one of said trunks.

3. In a telephone system, a group of outgoing trunks, a plurality of selective switches 120 each having access to said trunks, a common testing device, means for connecting said device to and disconnecting the same from the trunks of said group independently of said switches, means for connecting said device with any one of said switches, and means for operating the associated switch to select one of said trunks.

4. In a telephone system, a group of outgoing trunks, a number of selective switches 130

each having access to said trunks, means for extending a connection to one of said switches, a common testing mechanism, means for connecting said mechanism to and disconnecting the same from the trunks of said group for testing the same, means for connecting said mechanism to the particular switch to which connection is extended, and means for operating said switch to select one of said trunks.

5. In a telephone system, a group of trunks, a plurality of selective switches each having access to said trunks, a testing device common to said trunks and common to said switches, means for selectively connecting said device to the trunks of said group for testing the same, means for associating the device with any particular one of said selective switches, and means for operating said switch in accordance with the test made to select one of said trunks.

6. In a telephone system, a group of trunks, a number of switches, each having access to said trunks, a common testing mechanism, means controlled in accordance with numerical designations for connecting said mechanism to the trunks of said group for testing the same, means for connecting the mechanism with any one of said switches and means for operating the switch to select one of said trunks.

7. In a telephone system, a group of outgoing lines, a number of selective switches each having access to said lines, a common testing apparatus, means for connecting said apparatus to and disconnecting the same from the lines of said group for testing the same, means individual to the switches for connecting said apparatus to any one thereof, and means for operating the connected switch to select one of said outgoing lines.

8. In a telephone system, a group of outgoing lines, a number of selective switches each having access to said lines, a common testing mechanism, a multi-contact relay for connecting said mechanism to the lines of said group for testing the same, a multi-contact relay for connecting said testing mechanism to one of said switches, and means for operating the connected switch to select one of said lines.

9. In a telephone system, a group of outgoing trunks, a number of selective switches each having access to all of said trunks, a common testing equipment, a multi-contact relay for connecting said testing equipment with said trunks for testing the same, multi-contact relays individual to said switches for connecting said testing equipment to any one thereof, and means for operating the switch to select one of the trunks tested by said equipment.

10. In a telephone system, a group of outgoing trunks, a number of selective switches each having access to said trunks, a set of

common testing relays, means for associating said relays with and disassociating them from the trunks of said group for testing the same, means for associating said relays with any one of said switches, and means for operating the associated switch to select one of said trunks.

11. In a telephone system, a group of trunks, a plurality of selective switches each of which has access to said trunks, a set of common testing relays, means for connecting said relays to and disconnecting them from the trunks of said group, each relay serving to test a different one of said trunks, means for associating said relays with any one of said switches, and means for operating the associated switch to select one of said trunks.

12. The combination in a telephone system having a plurality of groups of trunks, of a number of switches, each having access to said groups, a common testing device, means for connecting said device to the trunks of any group for testing the same, means for associating the testing device with any of said switches, and means for operating the associated switch to select a trunk in the group tested.

13. The combination in a telephone system of a plurality of groups of trunks, a number of switches each having access to said groups, means for extending a connection to any one of the switches, a common testing mechanism, a variably operable device for connecting said mechanism to the trunks of any group for testing the same, means for connecting the testing mechanism with the particular switch to which a connection has been extended, and means for operating said switch to select a trunk in the group tested.

14. The combination in a telephone system of a plurality of groups of trunks, a plurality of selective switches each having access to said trunks, a common testing device, means controlled in accordance with numerical designations for connecting said device to the trunks of any group for testing the same, means for connecting the testing device to any one of said switches, and means for operating the connected switch to select a trunk in the tested group.

15. In a telephone system, a plurality of groups of trunks, a number of switches each having access to said groups of trunks, a common testing apparatus, multi-contact relays individual to said groups for connecting the testing apparatus to any one of said groups for testing the trunks thereof, multi-contact relays individual to said switches, for connecting the testing apparatus to any one of said switches, and means for operating the connected switch to select a trunk in the group tested.

16. In a telephone system, a group of trunks, a plurality of selective switches each

- having links for extending connections to said trunks, a common testing device, means for connecting said device to any switch for testing the links thereof and for testing said 5 group of trunks, and means for operating the selective switch to select one of the trunks tested.
17. In a telephone system, incoming trunks, outgoing trunks, a number of selective switches each having links for connecting the incoming trunks to any of the outgoing trunks, a common testing device, means for connecting said device to one of said switches for testing the links thereof and for testing 10 said outgoing trunks, and means for operating said switch to select an idle one of the outgoing trunks.
18. In a telephone system, a group of trunks, a number of selective switches each 20 having link circuits for extending connections to said trunks, a set of common testing relays, means for connecting said relays to any switch for testing the links thereof and for testing said group of trunks, and means for 25 operating said switch to select an idle one of the trunks.
19. In a telephone system, a group of trunks, a plurality of separate selective switches each having a number of links for 30 extending connections to said trunks, a common set of testing relays, means for connecting said relays to any switch for testing the links thereof and for testing such group 35 of trunks, each relay serving to test a particular link on any switch and a particular one of said trunks, and means for operating the selective switch to which the relays are connected to select one of the trunks.
20. In a telephone system, a plurality of outgoing trunks, a plurality of selective 40 switches each having links for extending connections to any of the trunks of said groups, a common testing device, means for connecting said device to any switch for testing the links thereof and for testing the 45 trunks of any group, and means for operating such switch to select one of the trunks in said group.
21. In a telephone system, a number of groups of trunks, a plurality of selective 50 switches each having links for extending connections to the trunks of any group, a common set of testing relays, means for connecting said relays to any of said switches for testing the links thereof and for testing the trunks in any one of said groups and means for operating such switch 55 to select an idle trunk in such groups.
22. In a telephone system, a group of trunks, a plurality of separate selective 60 switches each having a number of links for extending connections to said trunks, a common set of testing relays, means for connecting said relays to any switch for testing the links thereof and for testing such 65 group of trunks, each relay having two windings, one for testing a particular link on any switch and the other for testing one of said trunks, and means for operating the selective switch to which the relays are connected to select one of said trunks. 70

In witness whereof, we hereunto subscribe our names this 3rd day of November A. D., 1922.

SAMUEL B. WILLIAMS, JR.
EDWARD E. HINRICHSEN.
